UNITED STATES PATENT OFFICE.

HENRY HAASE, OF PHILADELPHIA, PENNSYLVANIA, ASSIGNOR TO THE
HENSEL, COLLADAY COMPANY, OF PENNSYLVANIA.

DESIGN FOR A SKIRT-PROTECTOR.

SPECIFICATION forming part of Design No. 29,689, dated November 15, 1898.

Application filed October 12, 1898. Serial No. 693,347. Term of patent 14 years.

To all whom it may concern:

Be it known that I, HENRY HAASE, a citizen of the United States, residing in the city and county of Philadelphia, State of Pennsylvania, have invented and produced a new and original Design for a Skirt-Protector, of which the following is a specification, reference being had to the accompanying drawings, forming part thereof.

10 The leading feature of my design for a skirt-protector is a head having thereon at the lower edge, or edge adjacent to the brush, rows of loops, and a portion of the face of said head appearing between the members of said 15 rows, and a row of loops at the upper edge of said brush, on the face thereof.

Figure 1 represents a side elevation of a piece of skirt-protector embodying my design. Fig. 2 represents a section thereof on line xx ,
20 Fig. 1.

In the drawings, A designates a piece of

skirt-protector, the same consisting of the head B, the brush C, the row of loops D at the upper or outer edge of said head, and the rows of loops E E at the lower edge, or edge 25 adjacent to the brush. The loops of the several rows curve one from the other in the direction of the length of said head.

The members of the rows of loops E are separated by a portion F of the face of the 30 head, appearing between the same as a divisional line.

Having thus described my invention, what I claim as new, and desire to secure by Letters Patent, is—

35 The design for a skirt-protector substantially as shown and described.

HENRY HAASE.
